FUEL PUMP FOR INTERNAL COMBUSTION ENGINES

Rudolf L'Orange, Stuttgart-Feuerbach,
GermanyApplication August 6, 1934, Serial No. 738,700
In Germany August 7, 1933

1 Claim. (Cl. 103—37)

This invention relates to a feed pump of the kind adapted to supply fuel at greater than atmospheric pressure to the spray pump of an internal-combustion engine, and its object is to provide simple and efficient means for maintaining the supply of the feed pump equal to the fluctuating demands put upon the spray pump.

This object is achieved according to the invention by arranging a reciprocating pump plunger 10 within a movable cylinder which is closed by a delivery valve and adapted to be displaced relative to the plunger, in opposition to a spring, by the pressure created by the plunger at the delivery end of an enclosing casing, the cylinder 15 being provided with suction ports which are opened and closed by the plunger and which, on a given displacement of the cylinder in opposition to the spring, remain closed so as to render the plunger stroke ineffective.

20 The accompanying drawing represents a vertical section of a pump constructed according to the invention.

The illustrated pump comprises a cylinder B which forms a sliding fit with an enclosing, upright casing A. The casing is provided with a fuel inlet K and with an outlet L, the latter being situated immediately above a member H which closes the lower end of the casing and forms a pressure chamber under the lower end of the cylinder. The communication of the cylinder with the pressure chamber is controlled by the delivery valve F which is supported by a spring G arranged between the valve and the closing member H. The cylinder is provided with suction ports J which are in constant communication with the inlet K. A reciprocating pump plunger C is arranged within the cylinder B and acts by alternately opening and closing the suction ports J. The plunger has a head N between which and a shoulder on the cylinder a spring D is arranged, which spring acts to produce the suction stroke of the plunger and also to oppose movement of the cylinder caused by fluid pressure at the pump outlet. The plunger bears against one end of an operating lever M which is rocked by a cam O preferably mounted on the shaft of a spray pump to which fuel is supplied by the plunger B. The inlet K communicates with a tank from which the fuel emanates.

50 The member H is provided with stops in the form of upright fingers P which limit the downward movement of the cylinder B.

In the illustrated position of the elements, the fuel is free to flow from the inlet K and through the ports J into the lower part of the cylinder

B. On the plunger C being lowered, the ports J are closed, and further movement of the plunger results in fuel being forced beyond the delivery valve F into the pressure chamber and thence through the outlet L to the spray pump. As 5 the action of the latter varies according to the power output of the engine, the spray pump may be unable to take all the fuel delivered by the plunger C, in which case the pressure in the pressure chamber will increase and cause the cylinder to be displaced in opposition to the spring D. At a given displacement of the cylinder, in opposition to the spring D, the plunger will be unable to open the suction ports, and the stroke of the plunger will thus be rendered ineffective. As 10 soon as the pressure is relieved the pump will resume its action. Normally the forces will be balanced so as to maintain the cylinder in a position which ensures the delivery of the correct quantity of fuel to the spray pump.

20 The arrangement has the particular advantage that the clearance space of the pump cylinder can be reduced to a minimum.

It is possible to arrange the cylinder and the casing in a horizontal position, and also in a 25 vertical position with the delivery valve situated at the top.

I claim:

A fuel pump for internal-combustion engines, comprising a cylindrical pump casing, a closing member for one end of said casing, the latter having axially spaced, lateral ports one situated near the closing member and serving as an outlet, the other port serving as an inlet, a pump cylinder arranged in and forming a sliding fit with said casing, the cylinder having lateral suction ports communicating with the inlet of the casing, stops on said closing member operative to keep the cylinder clear of the outlet of said casing, a spring-controlled delivery valve supported on the closing member and bearing against the end of the cylinder, a reciprocating pump plunger in said cylinder adapted to act by alternately opening and closing the suction ports, a 30 head on said plunger, a cam operated lever arranged to bear against said head for producing the pump stroke of the plunger, and a spring arranged to bear at one end against the plunger head and at the other end against the cylinder for producing the suction stroke, said spring being operative to urge the cylinder into contact with the stops and to yield to allow the cylinder to be displaced by pressure at the outlet until the suction ports can no longer be opened by 35 the plunger.

RUDOLF L'ORANGE.
